[57] CLAIM

The ornamental design for a jewelry clasp, as shown and described.

DESCRIPTION

FIG. 1 is a top plan view of a jewelry clasp, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top and left front perspective view thereof;

FIG. 7 is a top plan view of a main clasp member thereof;

FIG. 8 is a front elevational view of the main clasp member thereof;

FIG. 9 is a top plan view of an auxiliary clasp member thereof;

FIG. 10 is a front elevational view of the auxiliary clasp member thereof; and,

FIG. 11 is a top and right front perspective view thereof in an extended state, showing the state of use, with a choker shown in a phantom line.

A bottom plan view thereof not shown appears symmetrical to the top plan view.

The broken line showing of beads in FIG. 11 is for illustrative purposes only and forms no part of the claimed design.
